UNITED STATES PATENT OFFICE.

LORENZO H. GILSON, OF BROCKTON, MASSACHUSETTS.

INNERSOLE CHANNEL FILLER.

Application filed April 26, 1924. Serial No. 709,171.

This invention relates to leather channel filler strips for shoe bottoms, said strips being shaped in cross section to fill the channel of a welt innersole left open by lifting the channel flap and then trimming it at the inseam trimming operation. A shoe having a bottom including a channel filler strip of this character is disclosed and claimed in my co-pending application Serial No. 618,944, filed February 14, 1923. Such channels are of substantial depth and if it were attempted to form the filler strip out of a single thickness of leather, it would be necessary to cut it from relatively expensive stock.

According to this invention, therefore, the channel filler strip is built up from relatively thin, cheap material which may be of short lengths. The channels to be filled are of substantially triangular cross section and it is desirable that the filler strip be cut quite accurately, leaving clean, sharp edges. It is therefore desirable that all the edges of the strip be formed from the grain side portion of the leather since this is relatively close grained and uniform while the flesh side, particularly in the heavier grades of leather, is stringy and porous and often hard and relatively inflexible. It is evident that if a single thickness of leather of the desired width be cut diagonally to form two strips each of triangular cross section, two of the edges of one and one of the edges of the other, are formed from the flesh side of the material. By fixing together with their flesh sides toward each other a pair of relatively thin strips of leather to produce the desired thickness of strip, and cutting the compound strip diagonally, two channel filler strips each of triangular cross section are produced, all the edges of both of which being formed from the grain side portion of the leather. This is the method of building the filler strip contemplated by the present invention.

For a more complete understanding thereof reference may be had to the accompanying drawings in which

Figures 1 and 2 are plan and edge views of a leather strip.

Figure 3 is an edge view showing the

blank built up from short lengths of strip material.

Figure 4 is a plan of the same.

Figure 5 shows in plan the strip cut to narrower widths.

Figure 6 shows each of these widths again divided to form blanks rectangular in cross section.

Figure 7 is a perspective showing the blank cut on a diagonal to form filler strips of the desired triangular cross section.

Figure 8 is a similar view but showing the laminations partly separated in order to disclose the surfaces of the individual elements or laminations from which the filler strip is formed.

Figure 9 shows in perspective a piece of finished channel filler strip material.

Figure 10 shows in perspective a continuous length of such filler strip material wound on a reel.

Figure 11 represents a cross section of the forward portion of a welt shoe along the line 11-11 of Figure 12 and showing the filler strip in position.

Figure 12 illustrates a bottom plan of a lasted shoe before the outer sole has been fixed in position and showing the filler strip in position.

The procedure in building up the filler strips according to this invention is as follows. Relatively thin strips of leather 1 are prepared as in Figures 1 and 2, the strips, if desired, being cut from short lengths or scrap material. These strips are cemented together with their flesh sides toward each other, the joints 2 between the strips of each ply 3 being staggered so that a continuous length is produced as shown in Figures 3 and 4. When this length is of sufficient width it is then cut longitudinally as shown in Figures 5 and 6 the proper number of times to produce blanks of the desired rectangular cross sections as shown at 6 in Figure 7, each of a width equal to the width of the channel to be filled. It is preferable to cement the individual pieces together in relatively wide widths in order to avoid excessive handling and in order to facilitate the cementing of the parts together. Of course, if desired, however, the strips might be cut directly to the desired widths, pair

ticularly where it is desired to use material which is of insufficient width to form the wider strips therefrom. The strips 6, as shown in Figure 7, are then cut diagonally along the line 7 each to form two continuous channel filler strips of triangular cross section as shown at 8 in Figure 9.

It will be noted from an inspection of Figures 8 and 9 that each filler strip is formed of laminations 9 and 10, one of which is but one-half the width of the other, the dividing surfaces between the laminations as at 11 and 12, in the preferred form, being parallel to one face of the strip and presenting the flesh sides of the leather of which the individual laminations are composed. Since these flesh sides are cemented together, the edges of the strip which are exposed as at 15, 16, and 17 are all from the grain side of the material so that they may be cut clean and sharp.

The flesh sides being cemented together before the blank is cut diagonally are held in proper relationship and are not permitted to fray out and leave rough edges. The exposed edges of the finished filler strip are of material which is sufficiently flexible to permit the strip to be laid in the channel about the innersole as shown at 20 in Figure 12, thus completely filling this channel and producing a substantially smooth surface within the stitching rib 21 across the entire width of the innersole face as is shown more clearly in Figure 11. In this figure the innersole is shown at 25, the outer sole at 26, the lining and upper at 27 and the welt at 28.

The finished filler strip material may be

wound on reels as shown at 30 in Figure 10 and be laid in the innersole channels and cut off as desired from the continuous piece.

Having thus described this invention it should be evident that various changes and modifications might be made therein without departing from its spirit or scope as defined by the appended claims.

I claim:

1. A laminated leather strip of triangular cross section formed from grain leather and each edge of which presents the grain face of the leather.
2. An innersole channel filler strip of triangular cross section comprising a pair of strips of grain leather, one of which is but one-half the width of the other, secured together with their flesh sides in contact.
3. An innersole channel filler strip of triangular cross section comprising a pair of strips of grain leather secured together with their flesh sides in contact, the line of contact of said strips being substantially parallel to one face of the filler strip.
4. The method of making an innersole channel filler strip which comprises securing together layers of grain leather to form a continuous length of two ply material, the flesh sides of the plies being in contact, and cutting the length along a diagonal to form a pair of filler strips each of triangular cross section each edge of which is from the grain side portion of the leather.

In testimony whereof I have affixed my signature.

LORENZO H. GILSON.
